CLAIM

The ornamental design for a desktop organizer, as shown and described.

DESCRIPTION

FIG. 1 is a perspective view of a desktop organizer showing my new design;

FIG. 2 is a front view thereof;

FIG. 3 is a rear view thereof;

FIG. 4 is a plan view thereof;

FIG. 5 is a bottom view thereof;

FIG. 6 is a side view thereof;

FIG. 7 is a sectional view thereof taken along line 7—7 of FIG. 2; and,

FIG. 8 is a sectional view thereof taken along line 8—8 of FIG. 6.

The present invention is an easily portable desktop organizer in which, small articles on the desk, writing materials such as pencils, documents, files, and the like are put together. The desktop organizer is divided by inside walls into an upper part, a middle part, and a lower part. The middle part is optionally divided by detachable partitions. In the lower part, boxes for small articles are slidably provided.
